W. E. BARNES,
MUTE FOR MUSICAL INSTRUMENTS,
APPLICATION FILED APR. 28, 1919.

1,325,313.

Patented Dec. 16, 1919.

UNITED STATES PATENT OFFICE.

WILLIAM E. BARNES, OF CLEVELAND, OHIO.

MUTE FOR MUSICAL INSTRUMENTS.

1,325,313.

Specification of Letters Patent. Patented Dec. 16, 1919.

Application filed April 28, 1919. Serial No. 293,242.

To all whom it may concern:

Be it known that I, WILLIAM E. BARNES, a citizen of the United States, residing at Cleveland, in the county of Cuyahoga and 5 State of Ohio, have invented a certain new and useful Improvement in Mutes for Musical Instruments, of which the following is a full, clear, and exact description, reference being had to the accompanying drawings.

10 This invention relates to mutes for use with wind instruments such as cornets, trombones, etc.

It is a well known fact among musicians, and others familiar with the subject, that 15 mutes commonly used alter or disturb the pitch of the instrument and have a tendency when the mute is constructed of metal of introducing a metallic quality into the tone; and in muffling the tone and robbing it of 20 its richness and brilliancy.

It is the aim of this invention to produce a mute that will soften the tone to the desired degree and at the same time preserve its original pitch and smooth quality and 25 keep it free from any metallic sound.

A further object is to produce a mute at a comparatively low cost, possessing in addition to the foregoing advantages lightness, simplicity and durability.

30 To these ends I construct my mute of a hard but preferably non-metallic substance in thin sheet form shaped after the style of the frustum of a cone, and I close the larger, and outer, end with a vibratory dia-

35 phragm also of non-metallic material. Further, I provide the body of the mute with spacers of cork or the like that are compressed against the wall of the instrument when the mute is wedged into the bell there- 40 of, all of which will be readily understood by reference to the accompanying drawing and from the following detailed description.

In the drawing, Figure 1 is a perspective view of the mute; Fig. 2 is a section 45 through the bell of a wind instrument having my improved mute inserted therein; and Fig. 3 is a section on the line 3—3 of Fig. 2.

1 is the body of the mute which is of a frusto-conical shape and constructed prefer- 50 ably of what is known to the trade as “vulcanized paper.” The smaller end of the body is open, and the larger end is closed by a diaphragm 2 which I prefer at the present time to make of what is 55 known as “pressed board,” a cardboard composition that is hard and resilient. The

diaphragm 2 may be held in place by means of an annulus 3 of straw-board or the like, and in assembling the mute I glue the edge of the diaphragm 2 to the inner surface of 60 the annulus and then apply glue freely to the annulus and insert the same within the end of the body 1. In order to make the parts fit accurately, I bevel the outer surface of the annulus at an angle corresponding to 65 the taper of the wall of the body.

Near the smaller end of the body I glue or otherwise secure to it a number, preferably 3, of spacers or ribs 5. These may best be made of compressible material such as 70 cork. When the mute is so constructed, it may be forced into the bell 6 of a wind instrument in the position shown in Fig. 2, with the spacers or ribs 5 compressed against the wall of the instrument, as illustrated in 75 Figs. 2 and 3.

I find that a mute constructed as herein described and of the materials mentioned, softens or modifies the volume of a tone to the desired extent without disturbing its 80 pitch or altering its quality. It seems that the vibrating diaphragm 2 transmits to the external air the sound waves projected against it through the smaller end of the mute, and produces a tone corresponding to 85 the original one in quality though materially reduced in volume. Thus it will be seen that my improved mute possesses marked advantages over its more expansive yet no more durable predecessors. 90

Having thus described my invention, what I claim is:—

1. A mute of the character set forth comprising a frusto-conical shell, and a vibrating diaphragm closing the larger end of the 95 shell.

2. A mute of the character set forth comprising a frusto-conical shell of thin, hard, non-metallic substance, and a diaphragm closing the larger end of the shell. 100

3. A mute of the character set forth comprising a frusto-conical shell, a diaphragm closing the larger end of the shell, and means for spacing the shell from the wall of an instrument, as and for the purpose 105 specified.

4. A mute of the character set forth comprising a frusto-conical shell of thin, hard, non-metallic substance, a diaphragm closing the larger end of the shell, and spacers 110 of compressible material carried by the shell, as and for the purpose specified.

5. A mute of the character set forth comprising a frusto-conical shell, an annulus occupying the larger end of the shell, a diaphragm carried by the annulus, and means for spacing the shell from the wall of an instrument.

6. A mute of the character set forth comprising a frusto-conical shell, an annulus having its periphery beveled to correspond to the taper of the wall of the shell and arranged to be fitted within the larger end of the shell, and a diaphragm having its periphery attached to the inner side of the

annulus, and means for spacing the shell from the wall of an instrument, as and for 15 the purpose set forth.

7. A mute of the character set forth comprising a frusto-conical shell, an annulus glued within the larger end of the shell, a diaphragm having its periphery glued to the annulus, and means for spacing the shell from the wall of an instrument, as and for 20 the purpose set forth.

In testimony whereof, I hereunto affix my signature.

WILLIAM E. BARNES.
